UNITED STATES PATENT OFFICE.

FRANK T. RICE, OF TOWER CITY, NORTH DAKOTA.

EXTENSION SHADE AND CURTAIN-POLE HOLDER.

SPECIFICATION forming part of Letters Patent No. 613,605, dated November 1, 1898.

Application filed April 28, 1898. Serial No. 678,629. (No model.)

To all whom it may concern:

Be it known that I, FRANK T. RICE, of Tower City, in the county of Cass and State of North Dakota, have invented a new and Improved 5 Extension Shade and Curtain-Pole Holder, of which the following is a full, clear, and exact description.

The object of the invention is to provide a new and improved extension-holder for shades 10 and curtain-poles and which is simple and durable in construction, easily adjusted to windows of any width, and arranged for convenient attachment to the window-casing.

The invention consists of novel features 15 and parts and combinations of the same, as will be described hereinafter and then pointed out in the claims.

Reference is to be had to the accompanying drawings, forming a part of this specification, 20 in which similar characters of reference indicate corresponding parts in all the figures.

Figure 1 is a perspective view of the improvement extended ready for use. Fig. 2 is a front elevation of the improvement folded up. 25 Fig. 3 is an end elevation of a modified form of fastening device for the pole-bracket, parts being in section. Fig. 4 is an end elevation of one of the supporting-hooks with part of the frame in section, and Fig. 5 is a sectional plan 30 view of the same.

The improved holder is provided with a frame A, preferably made of wire, in two sections A' A², having parallel members A³ A⁴ and A⁵ A⁶, respectively, of which the members 35 A⁴ A⁶ are fitted to slide one upon the other, and the members A³ A⁵ are similarly arranged relatively to one another. The ends A⁷ A⁸ of the sections A' A² are made in U-shaped form, the side or end members being bent inwardly 40 along the corresponding members A³ A⁴ and A⁵ A⁶.

On the middle portions of the ends A⁷ A⁸ are pivoted the curtain-fixtures B B', respectively, of which the fixture B is formed with 45 the usual elongated slot B² for receiving the flattened trunnion of the shade-roller, the other fixture B' being formed with the usual aperture B³ for receiving the round trunnion of the shade-roller.

50 Each of the fixtures B B' is provided at its pivot end with offsets or flanges B⁴, adapted to abut against the end members of the ends

A⁷ A⁸, so as to limit the outward-swinging motion of said fixtures to hold the same approximately at a right angle to the frame A, 55 as is plainly indicated in Figs. 1 and 2. When the device is not in use, the fixtures B B' can readily be swung inward in alinement with the frame A, as is plainly shown in Fig. 2, to permit of conveniently transporting the holder 60 from one place to another and without the fixtures projecting from the frame and forming undesirable obstructions.

On the ends of the frame-sections A' A² are arranged means in the form of pins C C', as 65 shown in Figs. 1 and 2, or in the form of bolts C², as indicated in Fig. 3, for fastening the ordinary pole-brackets D to the frame A. As indicated in said Figs. 1 and 2, the upper pins C are bent upwardly to securely hold 70 the pole-brackets in place, it being understood that the pins engage the apertures in the pole-brackets usually engaged by the screws or nails for fastening the brackets to the window-casing. 75

In order to support the frame A on the window-casing, I provide hangers E, each formed at its upper end with a hook E', adapted to be driven into the window-casing at the top edge of the cross-bar, the hanger being also 80 formed at its lower end with a block E², grooved at its sides to engage the side members of a U-shaped loop A⁹, formed on the corresponding member A⁴ or A⁶ of the frame A. The upper end of the block E² forms a 85 seat for the middle portion of the loop A⁹ to securely hold the frame A in position. Two or more such loops A⁹ are preferably formed on each of the members A⁴ or A⁶ for fitting the hangers properly on narrow or wide window-casings. 90

It is evident from the foregoing that the device is very simple and durable in construction, can be cheaply manufactured, and readily extended according to the width of 95 the window on which the device is to be used. Furthermore, an ordinary pole-bracket can be readily attached to the frame at the ends thereof or removed therefrom whenever desired. 100

By having the curtain-roller fixtures B B' mounted to swing on the frame I am enabled to readily fold the said fixture up when transporting the device from one place to another;

but the said fixtures are always on the frame ready for use.

Having thus fully described my invention, I claim as new and desire to secure by Letters 5 Patent—

1. A shade and curtain-pole holder comprising a frame formed in two slidably-connected sections, each section having its outer end bent inwardly in the form of a **U**, shade-supporting fixtures pivotally mounted on each inwardly-bent end of the sections, each fixture having flanges adapted to engage with the sections to limit the outward movement thereof, the fixtures being capable of swinging inward in plane with the frame, two pins carried at the outer end of each frame-section, and pole-supporting brackets removably mounted on each pair of pins.

2. A curtain shade and pole holder comprising a frame formed in two sections slid-

able longitudinally on each other, each section having its outer end bent inwardly in the form of a **U**, a shade-holding fixture mounted to swing on each inwardly-bent end of the sections, each fixture having a flange serving to limit the outward movement thereof and the fixtures being capable of swinging into plane with the frame-sections, pins carried respectively by the frame-sections at points outward from the adjacent shade-holding fixtures, pole-supporting brackets carried on said pins, and a hanger for each frame-section, each hanger having a block and each frame-section having a loop with which the blocks are engaged, whereby to connect the 35 hangers with the frame-sections.

FRANK T. RICE.
